(57) **CLAIM**

The ornamental design for a stage intelligent light, as shown and described.

DESCRIPTION

FIG. 1 is a front perspective view of a stage intelligent light according to my new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof;

FIG. 7 is a bottom plan view thereof;

FIG. 8 is a partial enlarged view of Section 8 taken along the left side portion of the stage intelligent light shown in FIG. 1, the corresponding right side portion being a mirror image thereof; and,

FIG. 9 is another partial enlarged view of Section 9 taken along the front right side of the stage intelligent light shown in FIG. 1, the corresponding front left side being a mirror image thereof.

The broken lines shown in FIGS. 1, 2 and 3 illustrate portions of the stage intelligent light that form no part of the claimed design.
